Attorney

UNITED STATES PATENT OFFICE.

THOMAS W. MILLER, OF ASHLAND, OHIO, ASSIGNOR TO THE FAULTLESS RUBBER COMPANY, OF ASHLAND, OHIO, A CORPORATION OF OHIO.

SHOE LACING.

Application filed October 17, 1922. Serial No. 595,160.

To all whom it may concern:

Be it known that I, THOMAS W. MILLER, a citizen of the United States, residing at Ashland, county of Ashland, State of Ohio, have invented certain new and useful Improvements in Shoe Lacings, of which the following is a specification.

My invention relates to shoe lacings, and has for its object to provide an improved article of this character as hereinafter more definitely will be pointed out and claimed, reference being had to the accompanying drawing, in which:—

Figure 1 is a perspective view of one form 15 of my improved lacing, shown in packet form.

Figure 2 is a detail longitudinal sectional view of one end of said lacing.

Figure 3 is a transverse sectional view of 20 the same.

Figure 4 is a perspective view of a slightly modified construction of lacing.

Figure 5 is a fragmentary plan view of said modified construction.

25 Figures 6 and 7 are views similar to Figure 2 of the modified construction shown in Figure 4, taken at right angles to each other.

Figure 8 is a transverse sectional view of 30 said modified construction.

Similar numerals of reference denote corresponding parts in the several views.

In the said drawing, referring more particularly to Figures 1, 2 and 3, it will be 35 seen that my improved lacing 1 embodies a central core 2 of some flexible inelastic material, such as a fabric cord, the same being enclosed by a covering 3 of rubber, said covering forming an unbroken casing

40 for said core. In manufacturing my improved article a continuous length of core is coated with rubber in a tubing machine, in a manner similar to that in which rubber insulated copper wire is made, and after

45 leaving said machine, the lacings are cut the desired length, their ends then tapered to points by a rolling process or by dies, and the articles then vulcanized to the desired degree. Or, if desired, the tapering may

50 take place before the cutting into lengths, i. e., the rubber may be tapered down to the thickness of the embedded thread, after which the cutting to desired length will require only the cutting of the fabric cord.

55 In Figures 4 to 8 I have shown a slightly

modified construction, wherein the lacing 4 is flattened somewhat on two sides, as shown at 5 in Figure 8, and is formed with a series of ribs and depressions 6 on its opposite flattened faces, the same serving to prevent 60 the lacing from slipping and untying when in use, as readily will be understood. In said modified construction, the reference numeral 7 denotes the rubber covering, and 8 a plurality of fabric cords, the same being 65 shown as three in number, laid side by side better to obtain the flattened configuration.

My improved article can be manufactured to be sold at a comparatively low price, and will give more than ordinary service. A 70 further advantage is that it can be made in any color desired, and if it should become soiled in use, all dirt and discoloration can be removed with little effort by the means of a damp cloth, this advantage being of particular importance in connection with white or other light colored shoe laces. Furthermore, when a shoe is tightly laced there will be sufficient cushioning effect in my lacing to permit of some elasticity, thus adding 75 80 to the comfort of the wearer. A shoe lacing having a rubber covering made of one piece with the ends rolled or formed to points obviously will possess an advantage over a lacing with attached ends, in that there will 85 be no possible danger of the ends becoming detached, as is common with lacings now in use. Still another advantage is found in the fact that the rubber covering effectually will prevent any shrinkage of the lacing when 90 used in wet weather.

Having thus fully described my invention, what I claim as new and desire to secure by Letters Patent, is:—

1. A shoe lacing, embodying a flexible, 95 inelastic core, and a covering of rubber extending the entire length of said core and tapered at its ends.

2. A shoe lacing, embodying a flexible inelastic core, and a covering of rubber extending the entire length of said core, the covering at the ends of the lacing being 100 shaped to points.

3. A shoe lacing, embodying a flexible inelastic core, and a covering of rubber extending the entire length of said core, said covering being flattened substantially throughout its length and formed with ribs disposed at an angle to its length. 105

4. A shoe lacing, embodying a flexible 110

inelastic core, and a covering of rubber extending the entire length of said core, and rolled or formed to points at its ends, said covering being flattened substantially throughout its length and formed with ribs disposed at an angle to its length.

5. The method of forming shoe lacings, which consists in applying to a flexible in-

elastic core a covering of rubber extending the entire length of the same, then cutting ¹⁰ the same into lengths suitable for lacings, then tapering the ends of said lengths, and finally suitably vulcanizing said lengths.

In testimony whereof I hereunto affix my signature.

THOMAS W. MILLER.
